JAMES S. ATTERBURY AND THOMAS B. ATTERBURY, OF PITTSBURG, PENNSYLVANIA.

Design No. 4,298, dated August 23, 1870.

DESIGN FOR A LAMP-STAND.

The Schedule referred to in these Letters Patent and making part of the same

To all whom it may concern:

Be it known that we, JAMES S. ATTERBURY and THOMAS B. ATTERBURY, of Pittsburgh, in the county of Allegheny and State of Pennsylvania, have invented and produced a new and original Design for a Lamp-Stand, of which the following is a description, reference being had to the accompanying drawing making part of this specification, in which—

Figure 1 is a side view of the design.

Figure 2 is a top view.

Similar letters of reference indicate corresponding parts in the several figures.

The nature of our design consists of a straight fluted upper portion, A, an intermediate fluted downwardly-flaring portion, B, and a circular base portion,

C, the circumference of which is fluted, and its upper surface plain.

The straight upper portion A joins with the portion B by a bang, g.

a, b, and c represent the flutes, which are convex and clustered, as shown in fig. 1.

This design is intended as a foot or stand for a lamp-bowl.

We claim as our invention—

The foot or stand herein described.

JAMES S. ATTERBURY.
THOMAS B. ATTERBURY.
